UNITED STATES PATENT OFFICE

2,528,633

ROOFING AND CALCULATING SQUARE

Guy R. Anderson, Conley, Ga., assignor of five
per cent to W. F. McKinley, Atlanta, Ga.

Application July 21, 1948, Serial No. 39,869

2 Claims. (Cl. 33—97)

1

The present invention relates to roofing and calculating squares and it consists in the combinations, constructions and arrangements of parts herein described and claimed.

It is an object of the present invention to provide a calculating square particularly adapted for use by carpenters in laying out, measuring and cutting rafters and the like.

Another object of the invention is to provide a device of the character set forth which is simple in its construction and operation yet efficient and effective in use.

Another object of the invention is the provision of a device of the character set forth which will effect a great saving in time and at the same time allow for accuracy even by persons unskilled in mathematics in solving carpenters' roofing problems.

Another object of the invention is to provide novel means for locking the various parts of a device of the character set forth in preselected relative positions.

A further object of the invention is the provision of novel guide means for a pencil or the like in a device of the character set forth for marking rafters and the like for cutting.

Other and further objects of the invention will become apparent from a reading of the following specification taken in conjunction with the drawings, in which:

Figure 1 is a plan view illustrating one face of an embodiment of the invention.

Figure 2 is a plan view illustrating the reverse face of the device shown in Figure 1.

Figure 3 is a sectional view taken along line 3—3 of Figure 1.

Figure 4 is a sectional view taken along line 4—4 of Figure 1.

Figure 5 is a sectional view taken along line 5—5 of Figure 1.

Figure 6 is a sectional view taken along line 6—6 of Figure 1.

Figure 7 is a sectional view taken along line 7—7 of Figure 1.

Figure 8 is a fragmentary perspective view illustrating certain details of construction.

Figure 9 is an enlarged sectional view taken along line 9—9 of Figure 1.

Figure 10 is a fragmentary sectional view taken along line 10—10 of Figure 9, and

Figure 11 is an enlarged fragmentary sectional view taken along line 11—11 of Figure 1.

Generally there is provided a square having a quadrant integrally formed with the tongue and blade thereof and provided with a pair of ar-

cuate slots. At a point adjacent the juncture of the tongue and blade there is pivotally mounted in such manner as to be on either side of the quadrant a pair of arms interconnected through one of the arcuate slots by a rivet and then through the other arcuate slot by means of a locking bolt. A handle is slidably mounted upon the tongue of the square and is provided with a locking bolt for holding it in preselected positions thereon. A pair of calculating blades is slidably mounted in the handle at a right angle to the tongue of the square and so positioned as to each overlie one side of the quadrant. The curvular edge of the quadrant is provided with degree indicia and a series of slots extend from such indicia toward the tongue and at right angles thereto. The tongue, arms and the calculating blades are each provided with indicia on each exposed side thereof whereby the device may be utilized and read with either of its faces exposed to the operator and the device is particularly useful in calculating, for example, the proper length of rafters and the like from a given pitch and roof width and provision is made in the device for marking such rafter or the like by means of a pencil through slots provided in the quadrant for this purpose.

Referring now more particularly to the drawings, there is shown therein a square having a tongue 10 and a blade 11 having integrally formed therewith a quadrant 12 provided with the conventional arcuate outer edge 13 adjacent which on either side thereof is provided a scale 14 marked in degrees.

Upon an axle 15 mounted in the device at the center of the arc of the quadrant is revolvably mounted a pair of arms 16 and 17 contacting the opposite faces of the quadrant and interconnected through an arcuate slot 18 by means of a rivet 19 and also interconnected by a locking bolt 20 through an arcuate slot 21. One edge 22 of the arm 16 extends radially from the center of the axle 15 and a scale 23 is provided adjacent such edge 22. Likewise, one edge 24 of the arm 17 extends radially from the center of the axle 15 and a scale 25 is provided on the arm adjacent such edge 24.

Each of the scales 14 is provided with indicia 26 showing fine degree graduations thereon and from such indicia beginning with that indicating ten degrees and ending with that indicating eighty-five degrees, there extends in each case a slot 27 which is perpendicular to the tongue 10.

A scale 28 is provided on the tongue 10 on one side thereof and a scale 29 is provided on the

tongue along the other side thereof and a slot 30 is formed in the quadrant 12 adjacent the scales 28 and 29.

A handle 31 of generally rectangular shape is slidably mounted on the tongue 10 which is provided with a longitudinally extending groove 32 along one side thereof for the reception of a hook 33 formed at one end of a locking bolt 34, threaded in the handle 31 and having a knurled head 35 in an opening 36 in the handle 31.

Slidably mounted in the handle 31 perpendicularly to the tongue 10 is a pair of calculating blades 37 and 38 one of which overlies each face of the tongue 10 and quadrant 12 and which blades are fastened together at their outer ends by means of rivets 39. The blade 37 is provided with a scale 41 along one side edge thereof and the inner face of the blade 37 is provided with a groove 42 which receives therein a hook 43 formed at one end of a locking bolt 44 threaded in the handle 31 and having a knurled head 45 in the opening 36 in the handle 31.

In operation, it will be apparent that the arms 16 and 17 are rotated to a position where the edges 22 and 24 thereof indicate the pitch of a proposed rafter upon the scales 14 whereupon the locking bolt 20 is tightened to thereby lock the arms in such position. Thereafter the handle 31 is moved along the tongue 10 until, for example, the edge of the blade 37 having the scale 40 indicates upon the scale 28 the known span of the rafter, whereupon the head 35 of the locking bolt 34 is turned to thereby lock the handle 31 in such position upon the tongue 10. The blades 37 and 38 are then moved inwardly of the device until they contact the arms 16 and 17 whereupon the head 45 is turned to cause the locking bolt 44 to move its hooked end 43 into locking engagement with the side of the groove 42. The length of the rafter may now be ascertained by reading the scale 23 at the point of contact with the blade 37 and the height of the rafter at its upper end from the horizontal will be indicated by reading the scale 40 at its juncture with the slot 30. By placing the device in its now locked condition upon a board to be formed into a rafter as aforesaid in such manner that the arm 17 engages the upper side of such board, a pencil may then be run across such board to mark its bottom cut by utilizing the slot 30 as a guide.

To mark the upper cut in pencil upon the board the particular slot 27 adjacent the juncture between the arms 16 and 17 and the scales 14 is used as a pencil guide.

It will be understood that the scales 23, 25, 28, 29, 40 and 41 have indications in linear measure such as, for example, inches, feet, yards and the like and that the operation of the device when turned from its position indicated in Figure 1 to its position shown in Figure 2 will be identical with the only difference in the two sides of the device being a relative difference in the scales 28 and 29, the former having units of measure-

ment twice the size of the latter whereby the scale 28 is much easier to read with exactness but, it being necessary to double the reading of the scale 28 to secure a proper resulting figure.

While but one form of the invention has been shown and described herein, it will be readily apparent to those skilled in the art that many minor modifications may be made without departing from the spirit of the invention or the scope of the appended claims.

What is claimed is:

1. A device of the character described comprising a tongue, a blade formed integrally with the tongue, a quadrant interconnecting the tongue and blade and provided with a plurality of pencil-guiding slots, a pitch arm pivotally connected at the center of the quadrant at either side thereof and extending to the periphery thereof, a handle slidably mounted upon the tongue, a pair of calculating arms slidably mounted in the handle and lying one on either side of the tongue and quadrant perpendicularly to said tongue and indicia upon the quadrant on either side thereof adjacent the periphery thereof, indicia upon the pitch arms, indicia upon the calculating arms and indicia upon either side of the tongue, said pencil-guiding slots each being perpendicular to the tongue.

2. A device of the character described comprising a tongue, a blade formed integrally with the tongue, a quadrant interconnecting the tongue and blade and provided with a plurality of pencil-guiding slots each being perpendicular to the tongue, a pitch arm pivotally connected at the center of the quadrant at either side thereof and extending to the periphery thereof, a handle slidably mounted upon the tongue, a pair of calculating arms slidably mounted in the handle and lying one on either side of the tongue and quadrant perpendicularly to said tongue and indicia upon the quadrant on either side thereof adjacent the periphery thereof, indicia upon the pitch arms, indicia upon the calculating arms, indicia upon either side of the tongue, means for latching the handle to the tongue and means for latching the calculating arms in the handle.
